UNITED STATES PATENT OFFICE.

WILLIAM JOHNSON, OF HAVERHILL, MASSACHUSETTS, ASSIGNOR TO HIMSELF
AND HOSEA B. CARTER, OF EAST HAMPSTEAD, NEW HAMPSHIRE.

IMPROVEMENT IN RUFFLING-AND-HEMMING ATTACHMENTS FOR SEWING-MACHINES.

Specification forming part of Letters Patent No. 116,715, dated July 4, 1871.

To all whom it may concern:

Be it known that I, WILLIAM JOHNSON, of Haverhill, in the county of Essex and State of Massachusetts, have invented a new and useful Improvement in Ruffling or Gathering Device for Sewing-Machines; and do hereby declare the same to be fully described in the following specification and represented in the accompanying drawing, of which—

Figure 1 is a side elevation of a sewing-machine (or such parts thereof as are necessary to illustrate the nature and operation of my invention) as provided with the said device. Fig. 2 is a front elevation of the same. Fig. 3 is a top view of the device as detached. Figs. 4 and 5 are side elevations of the same.

To provide a simple and effective means of producing any desired degree of gathering or fullness of the ruffling, frilling, or puffing-strip or piece upon the ungathered band or fabric to which it is to be stitched is the object of my invention. My invention consists in the peculiar construction of the ruffler, and its combination with the presser-foot, or other equivalent device depending from the presser-foot bar, in such manner as to enable the said ruffler to be readily adjusted with respect to the ungathered band or material to which the ruffling is to be affixed, and to produce such frictional action upon such band as to so regulate its movement with reference to that of the ruffling or frilling portion as to insure any degree of fullness of the ruffling upon the band that may be desirable.

In the said drawing, A denotes the table of a sewing-machine; B, the goose-neck or curved arm which carries the presser-foot bar and needle-bar. D is the needle. E is a hemmer, which is applied to the said bar in lieu of the presser-foot, (either of which may be used with my device.) F is the cloth-supporting plate; and G, the feed device, so disposed as to work through the face thereof. R is the ruffler, which consists of a flat plate of metal, of a rectangular or trapezoidal shape, and is provided with a curved lip or cloth-guide, a, formed on one edge thereof. It also has a curved arm, H, by which it is affixed to the presser-foot bar C, by means of a screw, I, which passes through an oblong slot, J, formed longitudinally in the arm H, as seen in Figs. 4 and 5, and screws into the said bar. The said arm has two parallel flanges or wings, b b, which embrace the said bar on op-

posite sides, and serve to maintain the said ruffler in its proper position, or in parallelism with the cloth-plate F, both while stationary and while being moved up or down, as circumstances may require. There is also made through the face of the said ruffler an oblong seam-slot or passage, d, the needle D working through such, and near the inclosed end thereof. The said seam-slot is not coincident or parallel with the line of feed, but inclines toward the guide a, in the direction of the feed. The object of making such slot inclined is to cause the seam, in passing through such, to crowd the band to which the gathers or ruffling is to be stitched toward the guide, and maintain it in contact therewith, in those machines in which the area of feeding-surface is greater upon the material on the one side of the needle than that on the other side thereof, and thus compensate for the frictional tendency of such to draw the band away from its guide.

I do not limit my invention to its application to the presser-foot bar, as it may also be attached to the presser-foot when one is used, or to the hammer when it is employed.

The operation of my improved device is as follows: The ruffler or device being attached to the presser-foot bar, or a dependency therefrom, the strip or band from which the ruffle, frill, or puff is to be formed is to be laid upon the cloth-supporting plate, the lower face of the ruffler resting upon it; the piece or fabric to which the ruffling is to be attached is next laid between the top surface of the said ruffler and the presser-foot, or its equivalent, and the ruffler so adjusted, by means of its screw, with reference to the thickness of such piece or fabric, as to produce a greater or lesser degree of frictional action upon the same in accordance with the fullness or looseness of the gathering or ruffling required. If a slight fullness is sought the ruffler is so arranged to bear upon the material between it and the presser-foot as to cause but little friction upon it while passing between them. If a greater fullness of the ruffling is desired the ruffler is brought nearer the presser-foot, and so adjusted as to produce the requisite frictional action upon the said piece, and thereby retard the movement thereof, the under or ruffling-band or piece being gathered up or fed along with a uniform speed by the feeding device of the machine.

Thus it will be seen that, by my arrangement,

while the piece to be gathered in to form the frill or ruffle is moved at a given or uniform rate of speed, the band or fabric to which it is to be stitched is moved at such a relative rate as may be required to produce the desired fullness of gathers. By adjusting the device or ruffler to bear upon the band or ungathered fabric with only sufficient friction to keep it smooth while passing between it and the presser-foot, the two pieces will be simply sewed together without producing any ruffling or gathering whatever. By duly increasing the friction or pressure of the ruffler upon the fabric to which the ruffling is to be stitched, any desired fullness of the ruffling may be produced.

One great advantage resulting from the construction and arrangement of my device as described is that, not being affixed to the cloth-plate, as is usually the case, it offers no obstruction to the free manipulation of the ungathered band or fabric and the piece to be gathered in, so that the ruffling may be affixed to either side of the band with equal facility. Another important advantage which arises from the combination and arrangement of the ruffler with the hemmer, as shown, is that when it is desired to make a "finish" to the ungathered band the whole process of gathering, hemming, and stitching may be performed at a single operation; whereas, in the ordinary method, the gathering and stitching of the pieces are first effected, the two pieces being next

turned and finished by another line of stitching. By combining the ruffler and hemmer with the sewing-machine, as described, the presser-foot may be dispensed with, and either the ruffling and sewing of the two pieces may be accomplished in the ordinary manner when no hem or finish is required, or the gathering, hemming, and finish may be produced at one and the same time, as may be desirable.

I do not claim a ruffling device, irrespective of its construction; nor do I claim the interposition of a plate between the two pieces of fabric, one of which is to be gathered upon the other preparatory to being stitched thereto, as I am aware that such is not new; nor do I claim anything shown or described in Letters Patent No. 69,946 or 80,371, as my invention differs materially therefrom.

What I claim as my invention is—

1. The combination and arrangement of the adjustable ruffler R and the hemmer E with a sewing-machine, substantially as and for the purpose set forth.

2. The improved ruffler, as formed, with the inclined seam-slot d, as and for the purpose set forth.

WILLIAM JOHNSON.
